UNITED STATES PATENT OFFICE.

JOHN MICHAELS, OF WESTMOUNT, QUEBEC, CANADA.

DESK CONSTRUCTION.

1,372,626.

Specification of Letters Patent. Patented Mar. 22, 1921.

Application filed July 24, 1920. Serial No. 398,803.

To all whom it may concern:

Be it known that I, JOHN MICHAELS, residing at 322 Roslyn avenue, in the city of Westmount, in the Province of Quebec, in the Dominion of Canada, have invented a new and useful Desk Construction, of which the following is the specification.

The invention relates to desk construction, as described in the present specification and illustrated in the accompanying drawings 10 that form part of the same.

The invention consists essentially in the novel construction hereinafter more particularly set forth, whereby a low desk can be 15 readily converted to a high desk and reconverted, and the low desk of table form instantly covered.

The objects of the invention are to gain 20 all the advantages of a high desk and eliminate the permanent inconveniences thereof by its ready conversion into a low table desk to furnish more facilities for working and at the same time permit a change of position from a sitting posture to a standing posture 25 by raising the writing top, thus relieving the worker considerably, to furnish large and small establishments at a minimum expense, especially where many desks are required, by reducing the original cost as compared to roll top and high desks; and generally to provide durability, serviceability 30 and efficiency in desk construction.

In the drawings,

Figure 1 is a perspective view showing 35 one form of the construction and end piece supports.

Fig. 2 is a perspective view of an adjustable writing top showing a preferable form of the invention.

Fig. 3 is a perspective detail of a telescopic leg of the invention illustrated in Fig. 2.

Fig. 4 is a perspective detail of the writing top leg extension.

Fig. 5 is a cross sectional view of the leg 45 illustrated in the three preceding figures showing the operating means.

Like numerals of reference indicate corresponding parts in the various figures.

Referring to the drawings, in Fig. 1 the 50 desk is shown in a raised position with the end supports hinged and each formed of the several leaves 40 which are so many connected slats preferably joined by the canvas lengths 41, so that the raising and lowering 55 can be done to the height required and

the top held up to its extreme high position by the said end pieces fully extended.

This construction is new as applied to desks or boards, but the slat arrangement connected by canvas has been known in other directions. The carriage type of cover will serve to inclose the board as described and shown, or one of the other covers herein specified may be used in place of this collapsible top.

In Figs. 2, 3, 4, and 5 the desk or table 84, is supported on preferably rectangular or round telescopic legs 85 and 86, the sliding sections 85 being secured to the table 84 and the slide sections 86 standing on the floor and receiving the sections 85, the latter having vertical slots 87. The pulley shafts 88 extend through the slots 87 and are rigidly held on the leg sections 86 across the top and the pulleys 89 are journaled 75 on said shafts 88. The counterbalancing weights 90 are suspended by the cords 91 and the latter extend over the pulleys 89 and are attached to the bottom ends of the leg sections 85, therefore the board table 84 may 80 be easily raised and when up can be held in that position by the hinged supporting pieces 92 and 93 hinged to the cross rails 94 and 95 and to the table 84.

It is obvious that piano benches, and 85 special tables, come within the province of this invention.

It must be understood that without departing from the spirit of the invention, the features of construction may be somewhat 90 varied though not to any material extent, as it is necessary to reduce the weight of the top and vertically sliding portion of the desk at several points, particularly points adjacent to the longitudinal and lateral 95 edges, in other words the weight of the top portion must positively be to all intents and purposes eliminated, and in taking away the weight it must be done by distribution, and in this distribution, the support is to be near 100 the back and near to the front of the desk, and at the same time, near to the ends, otherwise it cannot be accomplished with any degree of satisfaction. The means employed herein described are weights and pulleys 105 which in themselves are very old devices and have been used in beds, couches and various articles of furniture, but the construction of the standing desk, useful for office, studio or any other work-room, has 110

not heretofore been known so far as I am aware as converted from a low flat top such as is universally used throughout the world, in fact, the only boards which have been 5 raised are in the form more of studio stands and old styles of desks, but to bring the top of a flat, low desk to an elevated position requires an ingenious distribution of weight whereby the exertion in raising the top is 10 minimized, and from all directions it will lift almost of itself.

What I claim is:—

1. A desk comprising a frame supported from the floor at each corner, a table top 15 having supports at each corner projecting downwardly into and vertically slidably in said frame supports adjacent to the longitudinal end edges, a plurality of cables engaging said table top supports at the lower 20 portions thereof, and mounted on pulleys for an upward pull of the table supports at the several corners of the table top, weights drawing on said cables and approximating the weight of the table and its supports, and 25 so arranged as to effect an even distribution of the balancing of the table top portion weight throughout its whole area, and end

pieces moving coincidently with the raising of the top and forming a rigid support between the frame and the top at the extreme 30 high position of the latter.

2. A desk comprising a frame supported from the floor at each corner, a table top having supports at each corner projecting downwardly into and vertically slidably in 35 said frame supports adjacent to the longitudinal end edges, a plurality of cables engaging said table top supports at the lower portions thereof, and mounted on pulleys for an upward pull of the table supports at the 40 several corners of the table top, weights drawing on said cables and approximating the weight of the table and its supports, and so arranged as to effect an even distribution of the balancing of the table top portion 45 weight throughout its whole area, and end pieces hinged to the top and moving into their positions coincidently with the raising of said top and forming end supports for said top in its extreme high position. 50

Signed at the city of Montreal, in the Province of Quebec, in the Dominion of Canada, this 13th day of July, 1920.

JOHN MICHAELS.
